UNITED STATES PATENT OFFICE

108,443

DESIGN FOR A TABLE LEG

Wolfgang Hoffmann, Batavia, Ill., assignor to The Howell Company, St. Charles, Ill., a corporation of Illinois

Application December 27, 1937, Serial No. 73,884

Term of patent 7 years

To all whom it may concern:

Be it known that I, Wolfgang Hoffmann, a citizen of the Republic of Austria, residing at Batavia, in the county of Kane and State of Illinois, have invented a new, original, and ornamental Design for a Table Leg, of which the following is a specification, reference being had to the accompanying drawing, forming a part thereof, wherein,—

Figure 1 is a side elevation of the table leg showing my new design; and

Figure 2 is a cross section therethrough, taken on line 2—2 of Figure 1.

The design consists of a pair of substantially straight and parallel tubes in adjacent relation, one tube near its lower end being extended through an arc toward the other tube to join therewith at the lower end thereof.

I claim:

The ornamental design for a table leg, as shown and described.

WOLFGANG HOFFMANN.
